UNITED STATES PATENT OFFICE.

LAWRENCE R. CHURCHILL AND WALTER W. CHURCHILL, OF DOLAND, SOUTH DAKOTA.

BURNER CONSTRUCTION.

1,295,124.

Specification of Letters Patent. Patented Feb. 25, 1919.

Application filed March 15, 1918. Serial No. 222,645.

To all whom it may concern:

Be it known that we, LAWRENCE R. CHURCHILL and WALTER W. CHURCHILL, citizens of the United States, residing at 5 Doland, in the county of Spink, State of South Dakota, have invented certain new and useful Improvements in Burner Construction; and we do hereby declare the following to be a full, clear, and exact description of the invention, such as will enable others skilled in the art to which it appertains to make and use the same.

The invention relates to a burner construction, and more particularly to the class 15 of steam generators and hydro-carbon burners for cooking stoves, ranges, furnaces or the like.

The primary object of the invention is the provision of a burner of this character, 20 wherein water and kerosene are preheated to generate steam and gas, which commingle for producing an inflammable fluid which when ignited possesses maximum heating quality and in this manner affording a saving in the consumption of kerosene and avoiding any waste thereof.

Another object of the invention is the provision of a burner structure of this character, wherein the parts thereof are readily 25 accessible and the arrangement thereof permits the easy mounting of the same within a stove, range, furnace or the like, the structure being novel in form to assure the successful and perfect working thereof.

30 A further object of the invention is the provision of a burner structure of this character, which is comparatively simple in construction, thoroughly reliable and efficient in its operation, and inexpensive to manufacture and install.

40 Other objects will be in part obvious and in part hereinafter pointed out.

The invention accordingly consists in the features of construction and arrangement of 45 elements, which will be exemplified in the construction hereinafter set forth, and the scope of the application of which will be indicated in the claim hereunto appended.

In the accompanying drawing:

50 Figure 1 is a fragmentary top plan view of a stove showing the burner construction constructed in accordance with the invention applied for,

Fig. 2 is a vertical longitudinal sectional view through the stove showing the burner 55 therein,

Fig. 3 is a perspective view of the burner detached from the stove.

Similar reference characters indicate corresponding parts throughout the several 60 views in the drawing.

Referring to the drawing in detail. A designates generally a portion of a cooking stove, which in this instance is of the range type and has formed therein as usual the 65 fire box 5 the same being accessible through the opening in the top of the stove and this opening is closed through the medium of a lid or stove plate 6, which is removably fitted within the opening in the ordinary 70 well known manner.

The steam generator and hydro-carbon burner comprises a pair of substantially U-shaped pipes 7 and 8 respectively which are disposed in cross relation to each other and 75 are adapted to depend within the fire box 5 in the stove A. The vertical limbs 10 and 11, respectively of each pipe are passed upwardly through suitable holes in the lid or stove plate 6 at opposite sides of the center 80 thereof and these limbs are secured or held fast to the plate in any suitable manner. Connected to the limbs 10 of the U-shaped pipes 7 and 8 are branch pipes 12 which have leads 13 from a double chambered 85 tank or reservoir 14 which is supported in any suitable manner at an elevated point on the stove or above the same. The pipes 12 are fitted with suitably manually operated cut-off valves 15 which control and shut off 90 the flow of fluid in said pipes. The reservoir 14 in its respective chambers are adapted to contain kerosene and water of any desired quantity.

Mounted on the limbs 11 of the U-shaped 95 pipes 7 and 8 are substantially goose neck shaped nozzles 16 the tips 17 of which are directed downwardly toward the center of the lid or stove plate 6, which latter is formed with a central opening 18 therein 100 and these nozzles 16 deliver kerosene and water interiorly of the fire box 5 through the opening 18 in the lid or stove plate 6.

Adapted to be contained within the fire box 5 to the desired height therein is a filling, preferably ashes, clay or the like 105

which is adapted to be impregnated by the water for the admitting of steam therefrom on the heating thereof. When the oil nozzle 16 is lighted the flame therefrom will play upon the U-shaped pipes 7 and 8 for generating steam which is admitted from the other nozzle and also the preheating of the oil to convert the same into gas, the U-shaped pipes 7 and 8 being designed to form the preheating sections of the burner attachment.

To operate the burner a fire is kindled within the fire box 5 of the stove by the use of oil so as to heat the U-shaped pipes 7 and 15 8 and the water contained in one of the pipes will be generated into steam while the oil in the other pipe will be preheated to convert the same into gas. The water ejected from one of the nozzles 16 into the filling 19 20 in the fire box 5 will become heated within the latter to generate steam therein and this steam will serve to heat the oil pipe for converting the oil into gas which is ejected from the other nozzle, a portion of the steam within the fire box 5 will commingle with the gas to assure proper combustion on the ignition of the gas in the heating of the stove for heating purposes.

It will be noted by reason of the arrangement of the oil burner nozzles 16 the flame when the oil is ignited will play directly upon the U-shaped pipes 7 and 8 for the heating thereof so that the water in one pipe

will generate steam while the oil in the other pipe will be converted into gas.

The fluid flowing through the pipes 12 is controlled by the valves so as to permit the flow to be regulated or shut off as the occasion may require.

From the foregoing it is thought that the 40 construction and manner of operation of the burner will be clearly understood, and therefore a more extended explanation has been omitted.

What is claimed is:—

The combination with a stove lid or plate having a central hole, of a burner comprising a pair of U-shaped pipes arranged in cross relation to each other and having their limbs extended upwardly through the lid or plate at points opposite each other and on opposite sides of the central hole, goose neck shaped nozzles detachably connected with the upper ends of a pair of the limbs with their free ends disposed within the central 55 hole within the plate or lid, means for supplying oil to one of the other or remaining pair of limbs, and means for supplying water to the other limb of the remaining pair.

In testimony whereof, we affix our signatures, in the presence of two witnesses.

LAWRENCE R. CHURCHILL.

WALTER W. CHURCHILL.
